Attorneys

UNITED STATES PATENT OFFICE.

SARAH KATZ, OF DETROIT, MICHIGAN.

ATTACHMENT FOR TELEPHONES.

Application filed February 9, 1926. Serial No. 87,055.

The invention relates to telephone attachments and has among its objects the provisions of a simply constructed device capable of ready attachment to a telephone of the present familiar type, the attachment having provision for supporting a memorandum pad, booklet, or the like, in position for convenient use while using the telephone. My invention also provides means for conveniently locating and supporting a pencil sharpener and supporting and retaining means for one or more pencils when not in use.

With these and other objects in view, the invention resides in the novel features of construction and combination and arrangements of parts as more fully hereinafter described and claimed.

Referring to the accompanying drawings in which like reference characters indicate corresponding parts:

Figure 1 is a perspective view showing my attachment applied to a telephone;

Figure 2 is a perspective view looking at the rear of the telephone and the attachment;

Figure 3 is a side elevation view of the attachment; and

Figure 4 is a plan view thereof.

In the drawings reference character A represents a telephone preferably of the well-known stand construction comprising, base 10, standard 11, transmitter 12, receiver 13 and receiver supporting hook 14.

My attachment comprises a bracket B preferably formed of a pair of clamping bands 15 and 16 surrounding the standard 11 and spaced vertically longitudinally thereof, the lower of said bands preferably being in engagement with the telephone base 10 for purposes of support. The bands 15 and 16 may be connected by one or more rods 17 fastened at their ends with the bands respectively as by solder. The central portions of the bands 15 and 16 may be clamped to the standard 11 by suitable means such as a clamping screw and nut 18 and 19 respectively.

The upper band 15 has its ends 20 and 21 extending in the opposite direction from

the hook 14 and receiver 13 for convenience as will be later apparent. The end 20 has mounted thereon, a pencil sharpener 22 which may be of the customary construction having an opening 23 for receiving the end 55 of the pencil to be sharpened. The end 21 of the upper clamping band is provided with a bracket 24 adapted to support a memorandum pad, booklet, or the like 25, the pad extending forwardly and downwardly for 30 convenient use. 26 represents a guide for the pages of the memorandum pad. The intermediate or clamping portion of the upper band 15 also has secured thereto as by 35 solder, a pencil supporting and retaining device 27 shown as a plurality of resilient coils of wire material or the like.

It will be noted that I have provided an attachment of simple construction and capable of convenient and ready attachment to 70 a telephone of the present standard type. In use, the operator may hold the receiver 13 in one hand and with his other hand remove one of the pencils 28 which are conveniently located at the front of the telephone. Furthermore, the memorandum 75 pad 25 is conveniently located and supported by my attachment in position for conveniently taking notes on the telephone conversation. The pencil sharpener provides 80 convenient means providing sharpening of the pencil with the free hand of the operator by simply rotating the pencil in the opening 23 as will be readily understood. If desired, the entire bracket may be formed by 85 one piece of material.

While it is believed that from the foregoing description, the nature and advantage of my invention will be readily understood, I desire to have it understood that I do not 90 limit myself to what is herein shown and described and that such changes may be resorted to when desired as fall within the scope of the claim.

What I claim as my invention is:

A combined note pad, pencil and pencil sharpener attachment for a telephone standard, said attachment comprising a bracket formed of a pair of clamping bands having 100 their central body portions surrounding the

standard and spaced vertically thereof, a spacing rod attached to and extending between said clamping bands, means for clamping said bands to the standard, and means on the upper of said bands whereby its central body portion is adapted to support a pencil rack, said upper band having

its end portions bent away in opposite directions from the central body portion and adapted to support a pencil sharpener and memorandum pad respectively.

In testimony whereof I affix my signature.

SARAH KATZ.
